UNITED STATES PATENT OFFICE

95,128

DESIGN FOR A TEXTILE FABRIC OR SIMILAR ARTICLE OF MANUFACTURE

John F. Gaul, Jr., Clifton, N. J., assignor to
Botany Worsted Mills, Passaic, N. J., a corporation of New Jersey

Application December 24, 1934, Serial No. 54,586

Term of patent 14 years

To all whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The characteristic features of my design consist of crinkles or undulations in a fabric in which

said crinkles or undulations lie in substantially the same general direction, and wavy or zig-zag bands or stripes of substantially equal amplitude running in substantially the same general direction with said crinkles or undulations and intersecting the latter at regular intervals, the wavy stripes or bands resulting from differences in levels of the crinkles or undulations.

I claim:

The ornamental design for a textile fabric or similar article of manufacture, substantially as shown and described.

JOHN F. GAUL, JR.
